Patented Mar. 3, 1970

216,734

JEWELRY FINDING

John J. Zajac, 2704 W. 24th Place, and Larry Kwiatek,
2647 W. 24th Place, both of Chicago, Ill. 60608

Filed Dec. 4, 1968, Ser. No. 14,792

Term of Patent 14 years

Int. Cl. D11—01

U.S. Cl. D45—1

FIG. 1

FIG. 2

FIGURE 1 is a front elevational view of a jewelry finding showing our new design; and

FIGURE 2 is an edge elevational view thereof.

The back is plain and unadorned.

We claim:

The ornamental design for a jewelry finding, as shown and described.
